FEDERICO VIDEGARAY, OF MEXICO, MEXICO.

SUPPORT FOR GARMENT-HANGERS.

1,159,342.

Specification of Letters Patent.

Patented Nov. 2, 1915.

Application filed May 24, 1915. Serial No. 29,961.

To all whom it may concern:

Be it known that I, FEDERICO VIDEGARAY, a citizen of Mexico, residing in Mexico city, Mexico, have invented certain new and useful Improvements in and Relating to Supports for Garment-Hangers, of which the following is a specification.

This invention relates to supporting means for garment hangers, and the object 10 of the invention is the provision of a device of the class described which shall be extremely simple in construction and mode of operation, of minimum weight, and yet, withal, highly efficient in the carrying out 15 of its functions.

The device of the present invention is particularly designed for use with wardrobe trunks, that is to say, trunks which may be used as wardrobes when stood upright, but 20 it may also be employed in wall cupboards, stationary wardrobes, and the like.

A salient feature of the invention resides in the fact that certain of the several elements which are combined to form the complete structure are separately capable of 25 performing different functions whereby the number of parts required is maintained at a minimum.

The invention may be briefly stated as 30 embodying a guide member adapted to be secured to the interior of a trunk or wardrobe, and with this guide member coöperates an extension member which, when in proper position, permits of the garments 35 adapted to be normally suspended upon the guide member to be withdrawn beyond the open side of the trunk or wardrobe and displayed to view in such manner that any desired garment may be easily and quickly 40 selected. The extension member is preferably so constructed and proportioned that, when the garments are in a normally packed condition within the wardrobe, said extension member may be utilized in forcing the 45 garments back into the wardrobe to allow of the closing of the door or cover and, at the same time, forcing the garments into intimate contact with one another whereby they are maintained in proper position, even 50 though the trunk or other container is carelessly handled.

With the foregoing features may also be combined a further pressing member which assists the extension member in maintaining 55 the garments in proper position when the cover or door is closed and which may have

the additional function of coöperating with the extension member so as to sustain the weight of the garments when in their exposed position exteriorly of the wardrobe.

In one of its practical forms, the invention embodies a tubular guide fixed beneath that end of the trunk which serves temporarily as the top. An extension rod, equal in length substantially to the width of the trunk, is adapted to fit interiorly of the tubular guide so that garment hangers may be suspended either upon the tubular guide or the extension rod, and may be shifted toward the free end of said rod to such extent as to bring all of said garments exteriorly of the trunk. When it is desired to close the trunk, the garment hangers may be forced back along the extension rod until they recede beyond the end of the guide member, at which time the extension rod may be removed and placed transversely of the trunk, against the garments, the opposite ends of said rod coöperating with clamping members which hold the rod tightly against the garments, thereby forming a kind of press to flatten the garments and hold them in position.

Features of the invention, other than those specified, will be apparent from the 85 hereinafter detailed description taken in conjunction with the accompanying drawings.

In the accompanying drawings, I have illustrated different practical embodiments 90 of the present invention, but the constructions shown therein are to be understood as illustrative, only, and not as defining the limits of the invention.

Figure 1 is a front elevation of a wardrobe trunk embodying the device of the present invention, showing the parts in their infolded, closed position. Fig. 2 is a vertical transverse section through the trunk, showing the parts in the position illustrated 100 in Fig. 1, said section being taken on line 2—2 of Fig. 1. Fig. 3 is a sectional plan view thereof, showing the parts in extended position, said section being taken on line 3—3 of Fig. 1. Fig. 4 is a perspective detail 105 of one of the guide supporting members. Fig. 5 is a side view of a slight modification of one of the details of construction, and Fig. 6 illustrates a portion of the foot member which is employed in one of the modified forms of the present invention.

Referring to the drawings, wherein the

adaptation of the present invention to a wardrobe trunk is shown. A designates a trunk which is shown in Figs. 1 and 3 as standing on end. A tubular sheath C is mounted in spaced relation to the upper end of said trunk and on the interior thereof by means of two hangers c and c', the former of which is positioned near the open side of the trunk, the latter being secured to the end 10 of the trunk near the back thereof. The sheath C is thus rigidly maintained in spaced, parallel relation beneath the top wall of the trunk and at such distance therefrom as to allow a number of garment hangers y 15 to be suspended thereon in such manner that they may be slid longitudinally of said sheath.

Coöperating with the sheath C is extension rod E which is of such size and shape 20 that one of its ends may be inserted within the tubular sheath, whereby in this position it serves as a track or supporting bracket on which the garment hangers may be slid to a position exterior of the trunk 25 i. e., into such position that the garments supported thereby will be exposed to view and the desired garment readily selected.

Aside from the function of serving as an extension or track for the support of the 30 garment holders when in coöoperative relation with the sheath, the supporting rod has an additional function, of a pressing member, when the garments have been moved to their concealed position within the trunk, 35 and it is desired to close the trunk. For this reason the extension rod E is made in length slightly less than the interior width of the trunk, and coöperating securing members d d' are secured in juxtaposition on the 40 interior of the opposite sides of the trunk in such position as to extend in parallel relation rearwardly from the open side thereof. The securing members are preferably formed from strap-metal being bent into the 45 form shown in Figs. 1 and 3, and each of said members is provided with a series of bayonet joints d², as shown in Fig. 2. The extension rod E, when serving the function of a pressing member, is adapted to be 50 positioned transversely of the trunk so that its opposite ends coöperate with the various bayonet joints of the respective members d d', whereby said rod may be positioned any distance from the back wall of the 55 trunk, desired.

The operation of the device, as thus far described, may be briefly set forth as follows: Let it be assumed that a plurality of garment hangers y with the garments which 60 they support are in exposed position upon the extension rod E, as shown in Fig. 3. When it is desired to pack and close the trunk the garment hangers are slid rearwardly along rod E and positioned in close 65 proximity to one another upon the sheath C.

If a large number of garment hangers is employed, it may be necessary to apply some force to the garment hangers to depress them within the confines of the trunk sufficiently to close the cover, and to lock them 70 in this compact form, the forward weight sustaining bracket c is preferably provided with a pin or rod g adapted for longitudinal sliding movement through alined apertures in said bracket c. It will be manifest from Fig. 4 that, when the rod is in a position shown in dotted lines, the hangers may be freely slid back and forth past the end of the sheath C, but when the rod g is in its full-line position, the foremost garment 80 hanger will engage with said rod, and thereby be precluded from disengagement with the sheath. When the garment hangers have been compactly positioned, as described, the locking rod g is shifted to the 85 full-line position, thereby maintaining the hangers in their compact positions. The extension rod E is then withdrawn and positioned transversely of the trunk slightly above the securing members d d', whereupon the rod is forced against the outermost garment to compress all of the garments into 90 compact relation interiorly of the trunk, and when the garments have been depressed as much as possible, the opposite ends of the 95 rod E are brought into engagement with the nearest bayonet slot d² for the purpose of locking the parts in position. When this has been accomplished, the garments and their hangers will have been forced to a 100 position interiorly of the open face of the trunk, and the cover may be closed.

It will be manifest from the foregoing that, when the parts have been positioned as described, the shifting of the garments is 105 absolutely precluded, no matter how roughly the trunk may be handled during transportation. Moreover, the device serves the same purpose as the well-known clothes-press, thereby keeping the garments in proper condition to be worn at all times.

While the device, as thus far described, operates with great efficiency, I have found that the employment of an additional feature somewhat increases the efficiency. The 110 feature referred to is shown in the drawings as embodied in a stirrup like member I. The stirrup like member I, which is shown substantially U-shaped in form, is provided with diverging free ends i, adapted to co-operate with apertures i' in supporting members J. Supporting members J are shown in the form of elongated bars, which are positioned on opposite sides of the trunk, and near the top thereof, and each of said 115 members is provided with a plurality of apertures i', into any two of which the opposite ends i of the stirrup may enter, as is clearly shown in Figs. 1 and 2. Stirrup I is resilient so that its free ends may be com- 120

125 130

pressed to allow of their withdrawal from the apertures i' , and, accordingly, said ends may be brought into engagement with any two of the apertures desired.

5 It will thus be apparent that, when it is desired to compress the garments within the trunk, the ends of the stirrup member may be positioned in such of the apertures i' as to give the proper pressure according to the 10 number of garments present, and thereafter the extension rod E, positioned as heretofore described, in such manner as to force said stirrup member against the garments as shown in Fig. 1. Thus the garments will 15 be compressed not only at their tops and bottoms by the hangers y and the rod E, but said stirrup I will also serve to exert pressure thereon. The garments will thus be more compactly held in position throughout a greater extent than in the previous 20 form, referred to, wherein the stirrup is omitted.

Like the extension rod E, the stirrup also 25 has a dual function, since, when the garments are hung in exposed position upon the extension rod E, as shown in Fig. 3, the stirrup member I may be removed from its normal, oscillatory position within the trunk, and slipped into guides I' at the upper 30 portion of said trunk into the position shown in Fig. 3. In this position, the outer end of the extension rod will rest upon the loop of the stirrup I, and will thus be supported thereby. However, when it is desired 35 to pack the trunk, the garments may be compressed to a position within the trunk, the stirrup removed from the guides I', its opposite ends positioned in the proper apertures i' , and the extension rod removed from 40 the sheath and positioned in engagement with said rod, thereafter being inserted into the adjacent bayonet slots d^2 for the purpose 45 of locking the parts in place. It thus appears that the stirrup member has a dual function, viz., assisting in the pressing of the garments, in the first instance, and the forming of an additional support for the garments when in exposed position, in the second instance.

50 The forming of various parts so that they are able to perform a plurality of functions obviously minimizes the cost of construction as well as the weight which, in the transportation of baggage, etc., is of considerable 55 moment.

To lighten the weight of the device and dispense with the lateral guides I', I may use two horizontal bars L of the type shown in Fig. 5. These bars may be of the same 60 general character as the supporting bars J, hereinbefore referred to, and provided with a plurality of apertures 1, into which the diverging ends i of the stirrup may be inserted. With this construction the main- 65 taining of the stirrup in a horizontal posi-

tion to support the outer end of the extension rod is effected by the pivotal pins 1' which are pivoted near the outer ends of bars L, and which are adapted, when the bar has been lifted to its horizontal position, 70 to be rotated into a position wherein the projecting fingers of said pins engage with the under surface of said stirrup. This is but one of the several changes which might be made, and, accordingly, the construction 75 shown in the drawing is to be understood as illustrative, only, and not as defining the limits of the invention.

A further modified form of the invention consists in the replacement of the stirrup 80 by a leg or foot member which embodies a rod composed of a plurality of sections m , joined together as shown in Fig. 6. The sections, when assembled, make a total length 85 equal substantially to the distance between the sheath and the surface on which the trunk is adapted to rest, when in its up- standing position. The rod is adapted to be positioned with one end on the floor and the opposite end beneath the outer end of 90 the extension rod E, whereby it serves to support said rod when the garments are in exposed position. The sections of which the rod is composed are, like the extension rod E, preferably made equal to the width of 95 the trunk, and complementary supporting members, similar to members d d' , are positioned at different heights along the sides of said trunk. Thus, when the trunk is packed, each section m may coöperate with 100 corresponding securing members to compress the garments at different portions of the length of the trunk.

It will be obvious from the foregoing that all of the parts coöperate in the performance 105 of their various functions to constitute a device of extreme simplicity, yet, withal, one of great merit and utility. The minimum number of parts employed, and the fact that the several parts coöperate with one another 110 to assist in the performance of the desired function allows of the manufacture of said parts from very light material, whereby the resulting structure does not materially add to the weight of a trunk wherein such parts 115 are not employed.

Having thus fully described the invention, what I claim as new, and desire to secure by Letters Patent, is:

1. In a device of the class described, the combination of a fixed guide for supporting a plurality of garment hangers, and a member coöperating with said guide for extending the length thereof, said member being detachable from said guide, for the purpose 125 of serving as a garment retainer for holding the garments in predetermined positions when detached from the guide.

2. In a device of the class described, the combination of a chamber, a fixed guide 130

mounted on the interior thereof for supporting a plurality of garment hangers, an extension member coöperating with said fixed guide for extending the same whereby the 5 garment hangers may be slid throughout substantially the length of the fixed guide and the extension member, and securing means mounted interiorly of the chamber, said extension member being removable 10 from the fixed guide and adapted to coöperate with the securing means for maintaining garments supported upon the garment hangers compactly within the chamber.

3. In a device of the class described, the 15 combination of a chamber, a fixed guide, equal in length substantially to the depth of the chamber, mounted on the interior thereof for supporting a plurality of garment hangers, an extension member coöperating with 20 said fixed guide for extending the same exteriorly of the chamber whereby the garment hangers may be slid to a position exteriorly of the chamber into exposed position, and securing means mounted interiorly of the 25 chamber, said extension member being removable from the fixed guide and adapted to coöperate with the securing means for maintaining garments supported upon the garment hangers compactly within the chamber.

30 4. In a device of the class described, the combination of a chamber, a fixed guide positioned in the upper portion thereof, and an extending and retaining rod slidably mounted on said fixed guide to form an extension 35 thereof, which extension projects to a point exteriorly of the chamber, whereby garment hangers normally supported upon the fixed guide may be moved to a position exteriorly of the chamber, on the extension 40 rod and said rod being removable from the fixed guide for the purpose of serving as a garment retainer for holding the garments, supported on the garment hangers, in predetermined positions when detached from 45 the guide.

5. In a device of the class described, the combination of a chamber, a fixed guide positioned in the upper portion thereof, a rod slidably and detachably mounted on said 50 fixed guide to form an extension thereof, which extension projects to a point exteriorly of the chamber, whereby garment hangers normally supported upon the fixed guide may be moved to a position exteriorly 55 of the chamber, and securing means positioned within the chamber and adapted to coöperate with the extension rod when the same is removed from the fixed guide for the purpose of compressing the garments 60 adapted to be supported upon the garment hangers.

6. In a device of the class described, the combination of a trunk, a fixed guide secured interiorly and at one end thereof, an 65 extension rod detachably secured to said

guide to project beyond the open side of the trunk, and clamping members positioned on either side wall of the trunk and adapted to hold the extension rod in a position transversely of the trunk when the same is removed from the fixed guide and brought into coöperation with said clamping members. 70

7. In a device of the class described, the combination of a trunk, a fixed guide secured interiorly and at one end thereof, an extension rod detachably secured to said guide whereby garment hangers may be slid from their normal position upon the guide member to a position exteriorly of the trunk and upon the extension rod, and means for detachably locking said garment hangers against such movement. 75

8. In a device of the class described, the combination of a chamber, a fixed guide positioned in the upper portion thereof, a rod slidably and detachably mounted on said fixed guide to form an extension thereof, which extension projects to a point exteriorly of the chamber, whereby garment hangers normally supported on the fixed 85 guide may be moved to a position exteriorly of the chamber, and means for normally maintaining said garment hangers in position upon the fixed guide interiorly of the 90 chamber. 95

9. In a device of the class described, a chamber, a fixed guide positioned in the upper portion thereof, a rod slidably and detachably mounted on said fixed guide to form an extension thereof, which extension projects to a point exteriorly of the chamber, whereby garment hangers normally supported on the fixed guide may be moved to a position exteriorly of the chamber, and means for normally maintaining said garment 100 hangers in position upon the fixed guide interiorly of the trunk, in combination with securing members positioned interiorly of the chamber and adapted to coöperate with the extension rod for the purpose of normally maintaining such garments as are supported on the garment hangers in compact 105 form interiorly of the chamber. 110

10. In a device of the class described, a chamber, a fixed guide positioned in the upper portion thereof, a rod slidably and detachably mounted on said fixed guide to form an extension thereof, which extension projects to a point exteriorly of the chamber, whereby garment hangers normally supported on the fixed guide may be moved exteriorly of the chamber, in combination with securing means positioned within the chamber and adapted to engage with the extension rod when the same is removed from the fixed guide for the purpose of maintaining the garments on the hangers in compact form within the chamber, and a pressing member adapted to coöperate with the extension rod when in its extended position to 115 120 125 130

support the outer end thereof and with said rod in its garment-compressing position to assist the same in compressing the garments.

11. In a device of the class described, a chamber, a fixed guide positioned in the upper portion thereof, a rod slidably and detachably mounted on the fixed guide to form an extension thereof, which extension projects to a point exteriorly of the chamber, whereby garments normally supported upon the fixed guide may be moved to a position exteriorly of the chamber, in combination with a stirrup member, means for rigidly supporting the stirrup member in substantially horizontal position and in contact with the extension rod near the outer end thereof for the purpose of supporting the free end of said extension rod, securing means, positioned interiorly of the chamber, adapted to coöperate with the extension rod when detached from the guide member for the purpose of compressing the garments within the chamber, and means within said chamber for allowing of the positioning of the stirrup member therein and in coöoperative relation with the extension rod to assist the latter in compressing the garments.

12. In a device of the class described, a chamber, a fixed guide for supporting a plurality of garment hangers positioned within said chamber, and a member coöoperating with said guide for extending the length thereof, in combination with a stirrup member provided with a pair of trunnions engaging with bearings positioned interiorly of the chamber, said member being removable from the guide and positionable within the chamber whereby it is adapted to coöperate with the stirrup member for maintaining the same in engagement with the garments within the chamber.

13. In a device of the class described, a chamber, a fixed guide for supporting a plurality of garment hangers positioned within said chamber, and a member coöoperating with said guide for extending the length thereof, said member being detachable from said guide, in combination with a stirrup member provided with a pair of trunnions engaging with bearings positioned interiorly of the chamber, and securing members positioned interiorly of the chamber and engaging with the extension member when said member is removed from the fixed guide, said securing members being so positioned that, when the extension rod is in such position, said rod engages with the stirrup member and maintains the same in intimate contact with the garments supported on the garment hangers.

14. In a device of the class described, the combination of a chamber, a fixed guide mounted on the interior thereof for supporting a plurality of garment hangers, an extension member coöoperating with said fixed

guide for extending the same exteriorly of the chamber whereby the garment hangers may be slid to a position exteriorly of the chamber, securing means positioned interiorly of the chamber, said extension member being removable from the fixed guide and adapted to coöperate with the securing means for maintaining the garments supported upon the hangers compactly within the chamber, and means coöperating with the extension rod in its extended position for supporting the free end thereof.

15. In a device of the class described, the combination of a fixed guide for supporting a plurality of garment hangers, a member coöoperating with said guide for extending the length thereof, said member being detachable from said guide and adapted to be positioned in engagement with the garments supported upon the hangers for maintaining them in predetermined positions, and supporting means coöperating with the free end of said extension member for precluding the sagging thereof when garment hangers are supported thereon.

16. In a device of the class described, the combination of a chamber, a fixed guide mounted therein for supporting a plurality of garment hangers, a member coöperating with said guide for extending the length thereof, and supporting means coöperating with the free end of said extension member for precluding the sagging thereof when garment hangers are supported thereon, said supporting means being also adapted to be positioned within the chamber and in engagement with the garments supported upon the hangers for the purpose of maintaining them in compact form interiorly of the chamber.

17. In a device of the class described, a chamber, a fixed guide positioned in the upper portion thereof, and a rod slidably and detachably mounted on the fixed guide to form an extension thereof, which extension projects to a point exteriorly of the chamber, in combination with a plurality of aligned bayonet slots on the opposite sides of the interior of the chamber and intermediate the ends thereof, whereby the extension rod, when detached from the fixed guide, may coöperate with any two oppositely disposed, complementary bayonet slots, when in engagement with garments supported on the hangers, for the purpose of maintaining said garments in compact form within the chamber.

18. In a device of the class described, the combination of a garment supporting member embodying two telescoping portions, brackets secured within a chamber and to one of said garment supporting portions for rigidly securing the same in position within the chamber, one of said brackets being so formed that, when the garment supporting

member is in its extended position, the garment hangers adapted to be hung on the supporting member are provided with an uninterrupted path of travel throughout the entire extent of said supporting member, the unattached telescoping portion being adapted to be removed from the fixed portion and positioned transversely of the chamber for maintaining the garments in predetermined positions.

19. In a device of the class described, a chamber, a fixed guide positioned in the upper portion thereof, and a rod slidably and detachably mounted on the fixed guide to form an extension thereof, which extension projects to a point exteriorly of the chamber, whereby garment hangers normally supported on the fixed guide may be moved

to a position externally of the chamber, in combination with a pair of retaining members, each of which is provided with a plurality of spaced bayonet slots and one of which members is positioned on each side and interiorly of the chamber and intermediate the ends thereof whereby the extension rod may be detached from the fixed guide and positioned interiorly of the chamber, with its opposite ends in engagement with two complementary bayonet slots and in engagement with garments supported on the hangers for the purpose of maintaining the garments in compact form.

In testimony whereof I have signed my name to this specification.

FEDERICO VIDEGARAY.
